CLAIM

The ornamental design for a bottle rack as shown and described.

DESCRIPTION

FIG. 1 is a front perspective view of the bottle rack;
FIG. 2 is a front elevation view thereof, the rear elevation
view being identical;

FIG. 3 is left side elevation view thereof, the right side
elevation view being identical;

FIG. 4 is a top plan view thereof;

FIG. 5 is a bottom plan view thereof; and,

FIG. 6 is front perspective view thereof shown in an
environment of use.

The broken lines showing a bottle in FIG. 6 illustrate
environment and form no part of the claimed design. All
other broken lines show portions of the bottle rack that form
no part of the claimed design.

1 Claim, 6 Drawing Sheets
